UNITED STATES PATENT OFFICE.

DAVID W. BURROUGHS, OF GREENFIELD, ILLINOIS.

HEDGE-TRIMMER.

SPECIFICATION forming part of Letters Patent No. 231,396, dated August 24, 1880.

Application filed November 29, 1879.

To all whom it may concern:

Be it known that I, DAVID W. BURROUGHS, of Greenfield, Greene county, Illinois, have invented a new and useful Improvement in 5 Hedge-Trimmers; and I do hereby declare the following to be a full and correct description of the same, reference being had to the accompanying drawings, in which—

Figure 1 is a side view of my improved 10 hedge-trimmer. Fig. 2 is a top view of the same. Fig. 3 is a detached view, showing the adjustable plate for setting the axle of the front wheel more or less obliquely, as desired. Fig. 4 is a horizontal section of the post that 15 supports the cutter-bar and gearing.

One object of my invention is to make a hedge-trimmer to run on a narrow embankment where horses cannot be used, and another is to increase the efficiency of the knives 20 and guards.

My invention consists in a novel construction and combination of parts, all as will be hereinafter fully described, and specifically pointed out in the claim.

25 My improved hedge-trimmer is mounted on two wheels, A B, and a simple frame, C, having a post, D, upon which the finger-beam E is vertically adjustable by means of a set-screw, F. This post has a slot for the set-screw and 30 is braced and strengthened by a clamping cap or plate, G.

The axle H of the front wheel is set obliquely to the line of travel, in order to resist the side sway of the cutters and finger-bar in working.

35 The inclination of the axle may be increased or diminished by means of the adjustable plate I, as represented in Fig. 4.

In order to give motion to the cutter, I employ the two beveled-gear wheels K and L and the crank M, or other means of applying power, and also the usual balance-wheel N, with crank-pin O and connecting-rod P, attached to the cutter-bar, as shown in Fig. 2.

45 The fingers or cutter-guards R are made broader in front, in order to prevent the hedge from slipping out, and thus escaping the stroke of the cutters or knives; and by clos-

ing these guards on the upper side of the knives and attaching them to the finger-beam E they are made strong and well adapted to 50 the work of trimming hedges.

It may be noticed in Fig. 2 that the hedge is caught by the acute angle of the fingers or guards, and cannot slip before the stroke of the cutters.

55 The arrangement of one wheel before the other, like the improved velocipedes or bicycles, adapts my hedge-trimmer to running on narrow embankments, where other hedge-trimmers cannot stand.

60 It is obvious that a very short axle, either in front or rear, might be used with two wheels thereon; but I prefer a single wheel for many reasons.

65 I am aware that a mower having the driving shaft and wheel and also the finger-bar inclined forward from a right angle, for the purpose of obviating side draft produced by the caster or grain wheel being so far from the center of draft of the cutter-bar, is old, and 70 such I distinctly disclaim as of my invention.

Having described my hedge-trimmer, what I claim is—

In a hedge-trimmer mounted on two wheels, one in front and the other in rear thereof, for 75 the purpose of running on embankments, the combination, with the supporting-frame and a reciprocating cutter-bar arranged above the axes of said wheels and at right angles to said frame, of the wheel A, mounted on an axle 80 arranged obliquely to the supporting-frame, and the slotted adjustable plate I, in which one end of the axle is journaled, provided with set-screws to secure it in position, substantially as and for the purpose herein shown and described.

85 The above specification of my said invention signed and witnessed at Greenfield this 11th day of November, A. D. 1879.

DAVID W. BURROUGHS.
